UNITED STATES PATENT OFFICE.

EDWARD B. LIGHT, OF DENVER, COLORADO, ASSIGNOR TO HIMSELF AND
EDWARD D. STODDARD, OF SAME PLACE.

IMPROVEMENT IN SADDLE-TREES.

Specification forming part of Letters Patent No. **222,514**, dated December 9, 1879; application filed
June 10, 1879.

To all whom it may concern:

Be it known that I, EDWARD B. LIGHT, of Denver, in the county of Arapahoe and State of Colorado, have invented certain new and useful Improvements in Saddle-Trees; and I do hereby declare the following to be a full, clear, and exact description of the invention, such as will enable others skilled in the art to which it pertains to make and use it, reference being had to the accompanying drawings, which form part of this specification.

My invention relates to a saddle-tree, and is designed to provide an improved construction which will be durable in use and adapted to answer the general purpose of devices of this character in an improved manner.

The improvement consists, first, in the combination, with a wooden tree-fork and a metallic horn whose base is hollow and fits over the tree-top, of a metal band whose extremities are fastened in position, together with a bolt which passes through said band, fork, and horn; second, in the combination, with a wooden tree-fork having a countersink formed in each side and a metal band having its extremities secured by bolts whose ends fit in said countersinks, of a metallic horn whose hollow base fits on the fork-top, together with a bolt which passes through said band, tree-fork, and horn, which latter is provided with a countersink in which the bolt-nut fits.

In the drawings, Figure 1 is a view, in perspective, of the invention. Fig. 2 is a vertical transverse section of the same.

The metallic horn A is made with the hollow base a, which fits down over the top of the tree-fork B, and is secured on the outer surface thereof. This wooden tree-fork is strengthened by the metal band C, fitted against its under side, and having its central upper portion secured in position by the bolt D. Said bolt passes through the band, the tree-fork, the hollow base of the horn, and up through the central portion of the neck of the latter.

A countersink, b, is formed in the top of the horn, within which works the nut c, which secures the bolt in its clamping action.

Each side of the tree-fork is formed with a countersink, d, and in the same is fitted the nut e, which locks its respective bolt f. These latter bolts f pass through suitable transverse holes formed in the tree-fork, the tree-bars, and the extremities of the band, thus securing the latter in place. A saddle-tree constructed in this manner is found to be strong, serviceable, and otherwise to admirably answer the purpose of the invention, as previously set forth.

Having fully described my invention, what I claim as new, and desire to secure by Letters Patent, is—

1. In a saddle-tree, the combination, with the wooden tree-fork and the metallic horn whose base is cast hollow and fits over the tree-top, of the metal band whose extremities are fastened in position, together with the bolt which passes through said band, fork, and horn, substantially as set forth.

2. In a saddle-tree, the combination, with the wooden tree-fork having a countersink formed in each side and the metal band having its extremities secured by bolts whose nuts fit in said countersinks, of the metallic horn whose hollow base fits on the fork-top, together with the bolt which passes through said band, tree-fork, and horn, which latter is provided with the countersink in which the bolt-nut fits, substantially as set forth.

In testimony that I claim the foregoing I have hereunto set my hand this 19th day of May, 1879.

EDWARD B. LIGHT.
